JEWELRY CHARM OR SIMILAR ARTICLE

Frank Kominik, 80-09 35th Ave., Jackson Heights,
Long Island, N.Y.

Filed Feb. 23, 1962, Ser. No. 68,950

Term of patent 14 years

(Cl. D45-17)

FIG. 1

FIG. 2

FIG. 3

FIG. 4

FIG. 1 is a front view of a charm or similar article showing my new design;

FIG. 2 is an edge view thereof;

FIG. 3 is a rear view thereof; and

FIG. 4 is a sectional view taken at line 4-4 of FIG. 1.

The dominant features of my design reside in the portions which are shown in full lines and include a movable object retained in the central portion and visible through a crystal.

I claim:

The ornamental design for a charm or similar article, as shown and described.
